TOOL FOR REMOVING STAPLES

William G. Pankonin, Chicago, Ill.

Original application December 12, 1932, Serial No. 646,846. Divided and this application February 6, 1936, Serial No. 62,614

7 Claims. (Cl. 254—22)

This invention relates to an improvement in staple removing tools.

The present application is a division of the co-pending application of William G. Pankonin, applicant herein, Serial No. 646,846, filed December 12, 1932, for Stapling machine patented October 27, 1936 as Patent No. 2,059,021.

One of the objects of this invention is to provide a device of this character which may be utilized to support the material into which a staple or fastener has been secured and to remove such staple while the material is so supported.

Another object is to provide a device of this character which may be made an appurtenance of a stapling machine by utilizing and incorporating as its own certain elements of such machine.

Other objects and advantages reside in certain novel features of construction, arrangement and combination of parts which will be hereinafter more fully described and particularly pointed out in the appended claims, reference being had to the accompanying drawing forming a part of this specification, and in which:

Figure 1 is a view partly in side elevation and partly in longitudinal central vertical section and illustrating a staple removing device embodying the present invention; and

Figure 2 is a detail view in section taken on line 2—2 of Figure 1.

Referring to the drawing, it will be seen that the device comprises generally a base 1, an arm 2 swingable to and from the base, a jaw member 3 secured to the arm, and a cooperable jaw member 4 mounted to move toward and from the jaw member 3.

The base 1 may be constructed as is generally known to those skilled in the art relating to desk type stapling machines. At one end of the base 1 is a mounting 5 providing means for pivotally or swingably connecting the arm 2 to the base 1. To maintain the free end of arm 2 normally raised from the base 1, a spring 6 is interposed between the arm and base and reacts therebetween. The upward movement of the arm 2 away from the base under influence of spring 6 is limited by any suitable abutment means known to those skilled in the art of stapling machines.

The arm 2 may also comprise a magazine for staples and have secured to its free end a housing and suitable staple driving mechanism therein, all as is fully disclosed in the application above

mentioned and as generally known to those skilled in the art.

On the free end of arm 2 is positioned in suitable manner the jaw member 3. In the embodiment illustrated, jaw member 3 comprises spaced teeth 7 and 7a, each of which has upwardly inclining camming surfaces 8 and 8a and lower anvil surfaces 9 and 9a. It should be noted that when the removing tool is constructed as an appurtenance of a stapling machine, the spaced teeth 7 and 7a may be formed by pressing out suitably shaped portions from the material forming the housing for the staple driving mechanism.

The cooperable jaw member 4 likewise comprises spaced teeth 10 and 10a each of which has upwardly inclining camming surfaces 11 and 11a and lower anvil surfaces 12. The spaced teeth 10 and 10a are oppositely related to the spaced teeth 7 and 7a and so positioned relative thereto that as they advance toward each other one set of teeth passes in between the other set. It is preferable, however, to have the teeth 10 and 10a pass in between the teeth 7 and 7a as the latter provide means for properly locating the staple and engaging the material into which it is secured.

To properly locate the teeth 10 and 10a with respect to the teeth 7 and 7a and to provide operating means whereby the cooperable jaw member 4 and the staple removing tool as a whole may be manually manipulated, the teeth 10 and 10a are each provided with a lever 13 extending upwardly therefrom. The levers are cross-connected by a connecting strip 14 and fulcrumed or pivotally mounted by means of a pin or other suitable means to supporting ears 15 attached to the free end of arm 2. When such arm also comprises an element of a stapling machine, the ears 15 may be attached to the housing of the stapling mechanism located thereon. The upper portions of levers 13 are also connected by a web structure 16 and are bent to provide a handle portion 17. To yieldably hold the cooperable jaw member 4 in spaced or staple receiving relation to the jaw member 3, a spring 18 is positioned to react therebetween. Suitable abutment means are provided to limit the extent of the spaced relation between said members.

The tension of spring 6 is so related to the tension of spring 18 that when pressure is applied to the handle portion 17, the free end of arm 2 will first be moved toward the base 1. Until this motion is arrested by the contact of the jaw member 3 with the base or with ma-

terial inserted between the arm and base, the co-operable jaw member 4 will not be moved toward the jaw member 3. Before the jaw member 4 under the influence of the above-mentioned 5 pressure starts to move relatively to jaw member 3, the latter will be urged toward the base 1 with sufficient force to engage therebetween material into which a staple has been inserted. Thereafter the jaw member 4 will move relative to jaw 10 member 3 to perform the staple removing operation.

The staple removing operation is described at 15 length in the co-pending application of William G. Pankonin, Serial No. 646,848, filed December 15 1932, for Tool for removing staples. It will be noted that on each tooth 7, 7a, 10 and 10a, the intersection of the upwardly inclined camming surfaces and lower anvil surfaces form sharp entering edges which are easily insertable 20 between the bridge portion of a staple and the material into which it is inserted. It is preferable that the outside overall width between teeth 7 and 7a be only slightly less than the distance between the insides of the legs of the staple or 25 staples, for the removal of which the device is designed.

After inserting on the base 1 and beneath the arm 2 material in which a staple is secured so 30 that the bridge of the staple lies beneath and slightly in front of the entering edges of the jaw member 3, pressure may be applied to handle portion 17 to first cause jaw member 3 to swing downwardly against the material to secure it in 35 position. In this position the entering edges of jaw member 3 are ready to enter under the bridge of the staple. Jaw member 4, upon continuous application of said pressure, is then swung toward jaw member 3 and its entering edge, by 40 reason of the established relationship between the jaw members, will enter under the bridge of the staple. Thereafter both jaw members co-operatively advance under the bridge of the staple. The upwardly inclining camming surfaces are caused to assert a lifting force on the 45 bridge of the staple and draw it upwardly while the lower anvil surfaces bear against the material into which the staple is inserted. If the legs of the staple are clinched beneath the material, the anvil surfaces acting through the material provide a support causing the legs to 50 straighten out sufficiently to prevent tearing of the material as the staple is removed. The base 1 may be provided with a depressed portion substantially below the jaw member 3 to provide a 55 clearance space designated at 19 which permits the clinched legs of a staple to freely straighten or unfold during the removing action. This depressed portion may be formed in any suitable manner and where the device is an appurtenance of a stapling machine it may be incorporated with the staple clinching anvil.

While constructions in which this invention 60 may be embodied have been shown and described, it is to be understood that these constructions 65 have been selected merely for the purpose of illustration and that various changes in the size, shape and arrangement of parts may be made without departing from the spirit of the invention or the scope of the subjoined claims.

70 The invention claimed is:

1. In a device of the type described, a base, an arm movable relative to said base, there being a jaw on said arm, said base, arm and jaw being positioned so that movement of said arm toward 75 and away from said base causes said jaw to move

into and out of abutting relationship with said base, and a second jaw independently co-operable with said first mentioned jaw and carried by said arm.

2. In a device of the type described, a base, an 5 arm pivoted to said base, there being a jaw fixed to said arm and a second jaw pivoted to said arm and co-operable with said first mentioned jaw, there being spring means urging said arm away from said base and said second jaw away from 10 said first mentioned jaw, whereby when manual force is applied to said second mentioned jaw said arm will move toward said base before said second mentioned jaw co-operably engages said first mentioned jaw. 15

3. In a device of the character described, a base, an arm pivotally mounted on said base, a staple engaging jaw on said arm and adapted to engage material into which a staple has been driven between itself and said base, an operating 20 lever pivoted to said arm, said lever having a jaw co-operable with said first mentioned jaw to engage therebetween a driven staple and remove the same, and spring means for biasing said arm and said lever to material and staple receiving 25 position, said spring means, arm and lever being related so that when force is applied to said lever to operate the same, said arm is first moved toward said base, thereby engaging the material, and then said second jaw moves toward said first 30 jaw to engage the staple.

4. In a device of the character described, a base, a jaw pivotally connected to said base and movable toward and away therefrom to receive material between itself and said base, and a second jaw pivoted to said first mentioned jaw and co-operable therewith to engage therebetween and remove staples from material, said second jaw having an operating handle, the action between said jaws and said arm being such that 40 when said handle is motivated said first jaw approaches said base and engages therebetween material into which a staple is driven, and then said second jaw approaches said first jaw engaging therebetween the staple and removes the 45 same from said material. 55

5. In a device of the type described, a base, and arm movable toward said base, a first jaw member on said arm, a second jaw member movable toward said first jaw member to remove a 50 staple from material in which it is clinched, said base and first jaw member engaging therebetween said material prior to the removing of said staple. 60

6. In a device of the type described, a base, and arm movable toward said base, a first jaw member on said arm, a second jaw member movable toward said first jaw member to remove a staple from material in which it is clinched, said base and first jaw member engaging therebetween said material prior to the removing of said staple, said base having a depressed portion below said first jaw member to permit clinched legs to freely unclinch. 65

7. A device of the type described, a base, an arm overlying said base and movable toward and away therefrom, a jaw on said arm, said jaw adapted to move into and out of abutting relationship with said base as said arm moves toward and away therefrom, and a second jaw carried 70 by said arm and movable into and out of co-operable relationship with said first-mentioned jaw independently of the relationship between the latter and said base.

WILLIAM G. PANKONIN. 75
